UNITED STATES PATENT OFFICE.

BENNO B. LEUSTIG, OF CLEVELAND, OHIO.

FLEXIBLE METAL CASING FOR LAMINATED SPRINGS.

1,235,211.

Specification of Letters Patent.

Patented July 31, 1917.

Application filed January 2, 1917. Serial No. 140,039.

To all whom it may concern:

Be it known that I, BENNO B. LEUSTIG, a citizen of the United States of America, residing at Cleveland, in the county of 5 Cuyahoga and State of Ohio, have invented certain new and useful Improvements in Flexible Metal Casings for Laminated Springs; and I hereby declare the following to be a full, clear, and exact description of 10 the invention, such as will enable others skilled in the art to which it pertains to make and use the same.

This invention relates to improvements in protective and lubricating flexible metal casings for laminated springs, and pertains more especially to a flexible sectional metal casing extending longitudinally of a laminated spring and serving as a covering for the top, sides and bottom of the spring.

One object of this invention is to provide means for insuring adequate lubrication of a laminated spring and minimizing the loss or waste of lubricant.

Another object is to provide means for protecting a laminated spring and excluding dust and dirt from the spring.

Another object is to render my improved flexible metal casing for a laminated spring simple in construction, readily applicable to 30 and removable from the spring and reliable in operation.

With these objects in view, and to the end of attaining any other object hereinafter appearing, this invention consists in certain 35 features of construction and combinations and relative arrangement of parts, hereinafter described in this specification, pointed out in the claims, and illustrated in the accompanying drawings.

In said drawings, Figure 1 is a side view

form a top covering for the uppermost leaf 55 of the laminated spring shown in Figs. 1, 2, 3, 4 and 5. Fig. 7 is a central longitudinal vertical section of a portion of two assembled flexible metal strips adapted to form a bottom covering for the spring. Fig. 8 is 60 a transverse section taken along the line 8—8, Fig. 6. Fig. 9 is a transverse section taken along the line 9—9, Fig. 7. Fig. 10 is a longitudinal section taken along the central leaf of the spring shown through the 65 hereinafter described flanges of the aforesaid strips. Portions are broken away in Fig. 10 to reduce the size of the figure. Fig. 1 is drawn on a smaller scale than the remaining figures.

Referring to Figs. 2, 3, 4 and 5 of said drawings, 12 indicates the uppermost leaf of one-half of a semi-elliptical or a quarter-elliptical laminated spring, and 13 indicates the leaves between said uppermost leaf and the bottom of the spring. The uppermost leaf 12 terminates at one end in a horizontally arranged tubular member 14 which forms the head of the spring, and at said head the spring is adapted to be attached 80 to the object which is to be mounted on the spring. The spring is reduced in size vertically in the direction of said head, and the upper of adjacent leaves of the spring projects in the usual manner outwardly beyond the lower of said leaves in said direction.

My improved protective and lubricating device for the spring illustrated (see Figs. 1, 2, 3, 4 and 5) comprises a flexible metal 90 casing which extends longitudinally of the spring and is composed of two superimposed flexible sheet-metal strips A and a arranged to form a double covering for the

15 flanges of the outer lower strip. Each
15 upper strip (see Figs. 4, 5, 6, 8 and 10) has
two laterally spaced rows of downwardly
projecting flanges, and B' indicates the
flanges of the inner upper strip, and b' the
flanges of the outer upper strip. The two
20 rows of flanges of each of said strips are ar-
ranged at opposite sides respectively of the
spring. The flanges of each row of flanges
of each casing-forming strip extend longi-
tudinally of the strip and are arranged in
25 line endwise and spaced longitudinally of
the strip. The flanges of each upper strip
are shown gradually reduced in width to-
ward their lower extremities. The flanges
of each lower strip are shown gradually re-
duced in width toward their upper extremities.

As shown in Figs. 4, 5 and 10, the two
rows of flanges A' of the inner lower strip
A overlap opposite sides respectively of the
35 spring, and said flanges extend from the bot-
tom to the top of the spring. The inner upper
strip B is wider than the inner lower
strip A. The space between adjacent flanges
of each row of flanges A' of the inner lower
40 strip A (see Fig. 10) is covered at its outer
side by a flange of the adjacent row of
flanges B' of the inner upper strip B, and

the space between adjacent flanges
of each row of flanges a' of the outer lower
strip A is covered at its outer side by a 80
flange of the adjacent row of flanges b' of
the outer upper strip b, and said flange of
said outer upper strip overlaps adjacent por-
tions of said adjacent flanges of said outer
lower strip and preferably extends from the 85
upper extremities to the lower ends of the
last-mentioned flanges. The flanges of each
row of flanges b' of the outer upper strip b
are spaced from the adjacent side of the
spring far enough to permit the illustrated 90
arrangement of the flanges of each row of
flanges a' of the outer lower strip between
the adjacent rows of flanges of the upper
strips.

It will be observed, therefore, that the 95
double covering formed for the bottom of
the spring by the lower strips A and a se-
cured together as hereinbefore indicated
comprises two laterally spaced rows of
flanges A' and a' at each side of the spring, 100
that the double covering formed for the top
of the spring by the upper strips B and b
secured together as hereinbefore indicated
comprises two laterally spaced rows of
flanges B' and b' at each side of the spring, 105
that each inner row of flanges A' of the bot-
tom covering and the adjacent outer row of
flanges a' of the top covering overlap each other.

between the adjacent side of the spring
the adjacent row of flanges of said inner
55 upper strip.

As shown in Figs. 4, 5 and 10, the outer
lower strip a is not only wider than the inner
lower strip, but wider than the inner
upper strip B. Opposite each flange of each
60 row of flanges B' of the inner upper strip
A is shown arranged (see Fig. 10) a flange
of the adjacent row of flanges a' of the outer
lower strip a , and said flanges of said outer
lower strip preferably extend from the
65 lower extremities to the upper ends of the

of the strips A, B, a and b is exaggerated
illustrated, but even sheet-metal strips as 120
thick as shown would have enough flexibility
to render the casing formed by them capa-
ble of flexing with the spring.

On the casing formed by the strips A, B,
a and b, adjacent the head 14 of the spring, 125
(see Figs. 1, 3 and 5) is loosely mounted a
sleeve consisting preferably of opposite end-
portions D and d of a flexible sheet-metal
strip having its central portion 17 extending
circumferentially of or embracing the head 130

14 of the spring. The end-portions D and *d* are oppositely arranged and serve as a covering for the adjacent end of the casing formed by the strips A, B, *a* and *b* and form 5 the top and bottom respectively of said sleeve, and the head-embracing member 17 of the sleeve-forming strip connects the sleeve-sections D and *d* together. The bottom sleeve-section D extends transversely of 10 the bottom and from side to side of the casing formed by the strips A, B, *a* and *b* and is provided at each side and externally of 15 said casing with an upwardly projecting flange 18, and the top sleeve-section *d* extends transversely of the top and from side to side of 20 said casing and is provided at each side and externally of said casing with a downwardly projecting flange 19 overlapping the outer side of the adjacent flange 18 of the bottom sleeve-section D.

The flanges 18 and 19 preferably extend, as shown in Figs. 1 and 3, beyond the casing formed by the strips A, B, *a* and *b* in the direction of the head 14 of the spring.

25 The sleeve-sections D and *d* and their flanges 18 and 19 and the connecting head-embracing member 17 form a protector and guard for the adjacent end of the casing formed by the strips A, B, *a* and *b* and also 30 operate to prevent the lodgment of dirt and dust on the head 14 and adjacent portions of the spring and aforesaid casing.

Means for preventing separation of the sleeve-sections D and *d* (see Fig. 5) comprise a bolt, the shank E whereof rests on and is arranged transversely of the top sleeve-section *d* and extends through the end-members *g* and *g* of a substantially U-shaped metal strap which has its central 40 member *G* engaging and extending transversely of the under side of the bottom sleeve-section D, and said strap has its central member *G* connected with each end-member *g* by an outwardly bowed resilient 45 member 21, and the resilient members 21 of said strap act to retain said central member *G* and the aforesaid bolt in their sleeve-engaging position, but obviously said resilient members permit a limited movement of the 50 sleeve-sections in the direction required to enlarge the space vertically between the sleeve-sections as desired to avoid interference with the flexibility of said sleeve, the spring and the casing composed of the strips 55 A, B, *a* and *b*. The end members *g* of the spring-strap project far enough above the top sleeve-section D to permit the extension of the shank E of the bolt therethrough, and said bolt has its head *e* arranged at the 60 outer side of one of said end-members, and a nut *f* is screwed onto said shank at the outer side of the other of said end members.

Means for preventing separation of the coverings comprising the strip A, *a* and B 65 *b*,—that is, means for holding said strips in

place relative to the spring near the head of the spring—comprise a bolt the shank H whereof (see Fig. 4) rests on and is arranged transversely of the outer upper strip a short distance inwardly from the hereinbefore mentioned sleeve-sections D and *d* and extends through the end members *l* and *l* of a substantially U-shaped metal strap which has its central member L engaging the under side and extending longitudinally of a metal cross-strip M which extends transversely of and is soldered or otherwise secured to the under side of the outer lower strip *a* and arranged (see Fig. 3) between downwardly projecting flanges *m* of said cross-strip, and said flanges prevent displacement of said strip longitudinally of the casing formed by the strips A, B, *a* and *b*. The central member L of said strap is connected with each end member *l* of the strap by an outwardly bowed resilient member 23, and the resilient members 23 of said strap act to retain said central member L and the aforesaid bolt H in their casing-engaging position, but obviously said resilient members 23 70 permit a limited outward movement of the strips A, B, *a* and *b* as desired to avoid interference with the desired flexibility of the spring and the casing composed of said strips. The end members *l* of the last-mentioned spring-strap project far enough above the outer upper strip *b* to permit the extension of the shank H of the bolt therethrough, and said bolt has its head *h* arranged at the outer side of said end members, and a nut I is screwed onto said shank 75 at the outer side of the other of said end members.

Obviously the leaves of the spring shown are not liable to be flexed at the inner end of the spring,—that is, at the end opposite to the end 14,—and as the strips forming each double covering of the spring are fastened together near said end of the spring there is little or no tendency of the strips 80 to separate from the spring at said inner end of the spring, but I would here remark that the spring and its casing are adapted to be clamped in any approved manner, upon the application of the spring, to the member or portion of a vehicle, frame or other object (not shown) to which the spring is to be attached, and obviously the strips composing said casing, when the casing has been clamped with the spring to said vehicle-member, 85 frame or other object, are positively held in place at said inner end of the spring.

By the construction hereinbefore described, it will be observed that the flexible inclosure formed by the strips A, B, *a* and *b* and its sleeve formed by the sections D and *d* protects the spring at the top, sides and bottom and forms a receptacle for holding lubricant and serves to minimize loss or waste of lubricant, and participates in keep- 90

ing the spring clean and adequately lubricated and in prolonging the life of the spring.

What I claim is:—

5. 1. The combination, with a laminated spring which has one of its leaves projecting beyond the other leaves of the spring and terminating in a head, and a casing comprising flexible metal strips extending longitudinally of the spring and into proximity to said head and forming a covering for the top, sides and bottom of the spring, of a sleeve mounted adjacent said head on the casing and comprising two sections extending across the bottom and top respectively of said casing, and a flexible member embracing said head and connecting said sleeve-sections together.
10. 2. The combination, with a laminated spring which has its uppermost leaf terminating in a head, and a flexible metal casing extending longitudinally of the spring and into proximity to said head and forming a covering for the top, sides and bottom of the spring, of a sleeve comprising a flexible bottom section and a flexible top section covering the bottom and top respectively of said casing adjacent said head, and a flexible member embracing said head and connecting
15. 30. said sleeve-sections together.
15. 3. The combination, with a laminated spring which has one of its leaves terminating in a head, and a flexible metal casing extending longitudinally of the spring and into proximity to said head and forming a covering for the top, sides and bottom of the spring, of a sleeve comprising a flexible bottom section and a flexible top section covering the bottom and top respectively of said casing adjacent said head, the sleeve-sections having overlapping flanges at the sides of said casing, and said flanges extending outwardly beyond the adjacent end of said casing in the direction of said head.
45. 4. The combination, with a laminated spring which has its uppermost leaf terminating in a tubular member arranged transversely of said leaf and forming a head for the spring, and a flexible metal casing extending longitudinally of the spring and into proximity to said head and forming a covering for the top, sides and bottom of the spring, of a sleeve comprising a flexible bottom section and a flexible top section covering the bottom and top respectively of said casing adjacent said head, and a member extending circumferentially of said head and connecting said sleeve-sections together, the bottom sleeve-section having two upwardly
50. 50. projecting flanges overlapping opposite sides respectively of said casing, the top sleeve-section having two downwardly projecting flanges overlapping the outer sides of the flanges of the bottom sleeve-section.
55. 5. The combination, with a laminated

spring, a flexible metal casing extending longitudinally of the spring and into proximity to a head of the spring and forming a covering for the top, sides and bottom of the spring, a sleeve comprising a flexible bottom section and a flexible top section covering the bottom and top respectively of said casing adjacent said head, and a member embracing said head and connecting said sleeve-sections together, of means for preventing separation of the sleeve-sections.

70. 6. The combination, with a laminated spring which has one of its leaves terminating in a head, and a flexible metal casing extending longitudinally of the spring and into proximity to said head and forming a covering for the top, sides and bottom of the spring, of a sleeve comprising a flexible bottom section and a flexible top section covering the bottom and top respectively of said casing adjacent said head, and a member embracing said head and connecting the sleeve-sections together, said head-embracing member and said sleeve-sections being formed of a single flexible metal strip.

80. 7. The combination, with a laminated spring which has its uppermost leaf terminating in a tubular member arranged transversely of said leaf and forming a head of the spring, a flexible metal casing extending longitudinally of the spring and forming a covering for the top, sides and bottom of the spring, and a sleeve comprising a flexible bottom section and a flexible top section covering the bottom and top respectively of the aforesaid casing adjacent the aforesaid head, of means for normally holding the sleeve-sections together and yieldable to permit a limited movement of the sleeve-sections in the direction required to enlarge the space vertically between said sections.

90. 8. The combination, with a laminated spring, of a flexible sheet-metal strip forming a covering for the bottom of the spring and extending longitudinally and from side to side of the spring and provided at each side of the spring with a row of upwardly projecting flanges which are spaced longitudinally of the spring, and a flexible sheet-metal strip forming a covering for the top of the spring and extending longitudinally and from side to side of the spring and provided at each side of the spring with a row of downwardly projecting flanges which are spaced longitudinally of the spring, the flanges of said strips having such relative arrangement and dimensions that said flanges cover the sides of the spring from top to bottom of the spring.

100. 9. The combination, with a laminated spring, of a flexible sheet-metal strip forming a covering for the bottom of the spring and extending longitudinally and from side to side of the spring and provided at each side of the spring with a row of upwardly

projecting flanges which are spaced longitudinally of the spring and reduced in width toward their upper extremities, and a flexible sheet-metal strip forming a covering for the top of the spring and extending longitudinally and from side to side of the spring and provided at each side of the spring with a row of downwardly projecting flanges which are spaced longitudinally of the spring and reduced in width toward their lower extremities, the flanges of said strips having such relative arrangement and dimensions that said flanges form a covering for the sides of the spring.

10. The combination, with a laminated spring, of a flexible sheet-metal strip forming a covering for the bottom of the spring and extending longitudinally and from side to side of the spring and provided at each side of the spring with a row of upwardly projecting flanges which are spaced longitudinally of the spring, and a flexible sheet-metal strip forming a covering for the top of the spring and extending longitudinally and from side to side of the spring and provided at the outer side of the aforesaid row of flanges with a row of downwardly projecting flanges which are spaced longitudinally of the spring and alternate with said flanges of the first-mentioned strip.

11. The combination, with a laminated spring, of a flexible sheet-metal strip forming a covering for the bottom of the spring and extending longitudinally and from side to side of the spring and provided at each side of the spring with a row of upwardly projecting flanges which extend substantially from the bottom to the top of the spring and are spaced longitudinally of the spring and gradually reduced in width toward their upper extremities, and a flexible sheet-metal strip forming a covering for the top of the spring and extending longitudinally and from side to side of the spring and wider than the first-mentioned strip and provided at the outer side of the aforesaid row of flanges with a row of downwardly projecting flanges which alternate with the first-mentioned flanges and are gradually reduced in width toward their lower extremities.

12. The combination, with a laminated spring, of a flexible sheet-metal strip forming a covering for the bottom of the spring and extending longitudinally and from side to side of the spring and provided at each side of the spring with a row of upwardly projecting flanges which are spaced longitudinally of the spring, and a flexible sheet-metal strip forming a covering for the top of the spring and extending longitudinally and from side to side of the spring and provided at each side of the spring with a row of downwardly projecting flanges spaced longitudinally of the spring, the space be-

tween and the outer sides of adjacent portions of adjacent flanges of each row of flanges of the first-mentioned strip being covered by a flange of the adjacent row of flanges of the second-mentioned strip.

13. The combination, with a laminated spring, of two superimposed flexible sheet-metal strips forming a double covering for the top of the spring and extending longitudinally and from side to side of the spring and provided each at each side of the spring with a row of downwardly projecting flanges which are spaced longitudinally of the spring, and a flexible metal covering for the bottom of the spring, the last-mentioned covering extending longitudinally and from side to side of the spring and provided at each side of the spring with a row of upwardly projecting flanges which are spaced longitudinally of the spring, said last-mentioned row of flanges being arranged between the adjacent rows of flanges of the aforesaid strips.

14. The combination, with a laminated spring, of two superimposed flexible sheet-metal strips forming a double covering for the bottom of the spring and provided each at each side of the spring with a row of upwardly projecting flanges which are spaced longitudinally of the spring, two superimposed flexible sheet-metal strips forming a double covering for the top of the spring and provided each at each side of the spring with a row of downwardly projecting flanges spaced longitudinally of the spring, the inner upper strip being wider than the inner lower strip, the outer lower strip being wider than the inner upper strip, the outer upper strip being wider than the outer lower strip, the space between and the outer sides of adjacent portions of adjacent flanges of each row of flanges of the inner lower strip being covered by a flange of the adjacent row of flanges of the inner upper strip, and the space between and the outer sides of adjacent portions of adjacent flanges of each row of flanges of the outer lower strip being covered by a flange of the adjacent row of flanges of the outer upper strip.

15. The combination, with a laminated spring, of an inclosure for said spring, said inclosure comprising a flexible metal covering for the bottom of the spring, which covering extends longitudinally and from side to side of the spring and comprises upwardly projecting members arranged at the sides and spaced longitudinally of the spring, the aforesaid inclosure also comprising a flexible metal covering for the top of the spring, said last-mentioned covering comprising downwardly projecting members arranged at the sides and spaced longitudinally of the spring, said projecting members of said coverings participating in the forma-

tion, at the sides of the spring, of the aforesaid inclosure.

16. The combination, with a laminated spring, a flexible sheet-metal strip forming a covering for the bottom of the spring and extending longitudinally and from side to side of the spring and provided at each side of the spring with a row of upwardly projecting flanges spaced longitudinally of the spring, and a flexible sheet-metal strip forming a covering for the top of the spring and provided at each side of the spring with a row of downwardly projecting flanges which are spaced longitudinally of the spring, of means operating to normally hold said strips in place relative to the spring and yieldable to permit limited outward movement of the strips.

17. The combination, with a laminated spring which has one of its leaves terminating at one end of the spring in a tubular member arranged transversely of said leaf and forming a head of the spring, of two superimposed flexible sheet-metal strips

forming a double covering for the bottom 25 of the spring and secured together adjacent the other end of the spring and extending longitudinally and from side to side of the spring and having upwardly projecting flanges at the sides of the spring, and two 30 superimposed flexible sheet-metal strips forming a double covering for the top of the spring and secured together adjacent the last-mentioned end of the spring and extending longitudinally and from side to side of 35 the spring and having downwardly projecting flanges at the sides of the spring, the flanges of said strips having such relative arrangement and dimensions that they form a covering for the sides of the spring. 40

In testimony whereof, I sign the foregoing specification, in the presence of two witnesses.

BENNO B. LEUSTIG.
